US00D617198S

(12) **United States Design Patent**
Lee et al.

(10) **Patent No.:** **US D617,198 S**
(45) **Date of Patent:** **** Jun. 8, 2010**

(54) **BOTTLE**

(75) Inventors: **Noel Lee**, Las Vegas, NV (US); **Tim Pryde**, San Francisco, CA (US); **Dan Hua**, San Jose, CA (US)

(73) Assignee: **Monster Cable Products, Inc.**,
Brisbane, CA (US)

(**) Term: **14 Years**

(21) Appl. No.: **29/319,635**

(22) Filed: **Jun. 11, 2008**

(51) **LOC (9) Cl.** **09-01**

(52) **U.S. Cl.** **D9/529; D9/453**

(58) **Field of Classification Search** D9/416,
D9/417, 422, 424, 430, 431, 434, 435, 451,

(57) **CLAIM**

The ornamental design for a bottle, as shown and described.

DESCRIPTION

A portion of the disclosure of this patent document contains material which is subject to copyright protection. The copyright owner has no objection to the facsimile reproduction by any one of the patent document or the patent disclosure, as it appears in the Patent and Trademark Office patent file or records, but otherwise reserves all copyright rights whatsoever.

FIG. 1 is an exploded perspective view of a bottle with the top cap removed showing our new design;

FIG. 2 is a perspective view of a bottle with the top cap;

FIG. 3 is a front elevation view thereof;

FIG. 4 is a rear elevation view thereof;

FIG. 5 is a side elevation view thereof;

FIG. 6 is an opposite side elevation view of FIG. 5;

FIG. 7 is a top plan view thereof; and,

FIG. 8 is a bottom plan view thereof.

The broken line showing of an interior spray pump and bottom of a bottle is included for the purpose of illustrating only and forms no part of the claimed design.
